ADHESIVE APPLYING DEVICE FOR CASE
CLOSING AND SEALING APPARATUS

Kaye Holstebroe, Gildersleeve, and Edgar Ardell and Ludwig Wimmer, Middletown, Conn., assignors to Emhart Manufacturing Company, a corporation of Delaware

Original application August 7, 1946, Serial No. 688,950. Divided and this application March 13, 1951, Serial No. 215,308

6 Claims. (Cl. 118—220)

1

This invention relates to adhesive applying devices and more particularly to devices for applying liquid adhesive material to upright or vertical surfaces, such, for example, as the flaps of shipping cases or cartons. Shipping cases are usually made of corrugated board or fibre board, having one or more of their faces, for example, the top and bottom faces of the case closed by flap extensions from the body of the case. To prepare the filled case for shipment, such flaps are folded against one another and held in place by suitable adhesive.

In certain types of apparatus for automatically closing and sealing shipping cases, it is necessary or desirable to apply liquid adhesive to certain of the flaps while they are in an upright and usually vertical position. The handling of liquid adhesive and applying it in the desired thin uniform coating on the vertical flap surface presents something of a problem. Various mechanisms have heretofore been proposed for accomplishing this, but for one reason or another they are not entirely satisfactory. Accordingly, the prime object of the present invention is to provide an improved device or mechanism, by means of which liquid adhesive can be coated upon the surfaces of one or more flaps while in the vertical position.

This application is a division of applicants' copending application, Serial No. 688,950, filed August 7, 1946, for "Case Closing and Sealing Apparatus" and now abandoned, and the invention will be described in connection with the sealing apparatus disclosed in that application. Such apparatus together with the improved adhesive applying mechanism is illustrated in the accompanying drawings, in which:

Fig. 1 is a view of the carton closing and sealing apparatus in longitudinal section on line 1—1 of Fig. 2 with the side frame removed but showing the frame upright members;

Fig. 2 is a view in horizontal section taken on line 2—2 of Fig. 1;

Fig. 3 is a plan view of the apparatus shown in Fig. 1;

Fig. 4 shows a modified form of glue applying mechanism and is a view in section taken on line 4—4 of Fig. 5. It is also a fragmentary vertical transverse section with respect to Fig. 1 and is drawn to about the same scale as that figure;

Fig. 5 is a sectional view of this modification drawn to a larger scale than Fig. 4, taken on broken line 5—5 of Figs. 4 and 6;

Fig. 6 is a vertical section of the modification taken on line 6—6 of Fig. 5;

2

Fig. 6a is a fragmentary top view showing a detail;

Fig. 7 is a horizontal section taken on line 7—7 of Fig. 6.

Referring now to the accompanying drawings, the apparatus is divided into sections. The flap heating section is indicated by reference character A, while B indicates the adhesive applying section, C the flap folding section and D the sealing pressure applying or compression unit section. A case slideway, indicated generally by reference numeral 1 extends from end to end of the apparatus interconnecting these four sections. The entrance is at the right as viewed in Figs. 1, 2, and 3 and the discharge at the left. The shipping cases are received on a roller supporting table 2 at the entrance end and pass from table 2 onto another roller table 3 which is within the flap heating section A.

From the beginning of the adhesive applying section B and continuing through the flap folding section C the cases are supported on a smooth stationary plate 4, the left-hand end portion 5 of which is tapered to a rounded point and is customary to facilitate the folding of the bottom flaps. In the sealing section D the cases are supported on a wide belt 6 which extends throughout sealing section D and is in turn supported on a series of closely spaced rollers 7. Belt 6 moves freely on rollers 7 and is shifted forward by the movement of the case.

The cases are propelled through the slideway 1 and along the roller table 3, stationary plate 4 and belt 6 by means of a pair of power operated conveyer chains 8 which have spaced flight bars 9 extending between them to engage the rear of the cases and push them forward. Chains 8 travel in horizontal supporting channels 10 (Fig. 1) throughout the length of slideway 1, these channels being appropriately supported on the frame of the machine which consists essentially of four upright channel posts 11 joined together by suitable longitudinal and transverse tie-bars.

At the front or receiving end of the slideway chains 8 are supported on sprockets 12, and at the discharge end they pass over smaller sprockets 13 and engage a pair of large drive sprockets 14 which are supported on a cross shaft 15. Chains 8 then are directed downwardly to a point near the bottom and are trained around guide sprockets 16 and take-up sprockets 17 and 18 to the front end of the machine where they pass around a second pair of take-up sprockets 19. The cases are main-

tained in transverse alignment with the operating parts of the several sections A, B, C, and D by means of upper and lower sets of adjustable guide bars or rails 20 (Fig. 1).

Shaft 15 which turns the drive sprockets 14 for the conveyer chains 3 is driven by an electric motor 21 which is operatively connected to shaft 15 through a speed reducing gear 22. Motor 21 drives the reducer input shaft 15 through a belt 23 and the slow speed or output shaft 24 of the speed reducer is chain connected to shaft 15 by means of a sprocket chain 25 operating on suitable sprockets on the respective shafts.

Electric motor 21 is not operated continuously but intermittently and automatically under the control of the case entering the machine. That is to say when a case enters the flap heater section A it engages and closes a normally open starting switch 26 and the machine operates through a pre-determined cycle of movement as determined by the control mechanism (not shown). This cycle of movement includes a pre-determined limited operation of the conveyer chains 3 together with the operation of the sealing pressure applying mechanism D, all of which will be more fully described later.

The operator of the machine stands at one side of the roller table 2 and may pack the container by hand, while on this table, or the filled cases may be fed automatically to table 3 by mechanism such as shown in U. S. Patent No. 2,324,401 operated in timed relation to conveyer 3. In the event that the cases are hand packed the operator receives a supply of the bars of soap, food packages, or other articles on a suitable conveyer within her convenient reach near roller table 2. The operator first squares out by hand a shipping case blank placing it on roller table 2 with its inner bottom flaps closed and with its outer bottom flaps hanging down along each side of the roller table. The inner and outer top flaps the operator folds outwardly where they are held by their own weight and resiliency during the insertion of the articles in the case.

After the case is filled the operator folds the inner top flaps against the contents of the case and pushes the filled case by hand from roller table 2 onto roller table 3. The side of the case strikes the lever of starting switch 26 closing the switch and shortly a flight bar 9 carried by chains 8 rises around sprockets 12 and, engaging rear end of the case, pushes it forward to the left to the flap heating position shown in dotted lines in Fig. 1 and designated by the letter H. As the case enters the machine the downward hanging bottom outer flaps 28 which have a natural tendency to bend toward one another, are forced outwardly to vertical position by flap guides 29 (Fig. 2) which form parts of the lower flap heaters.

The top, side or outer flaps 30, which naturally assume some such position are also swung to vertical position, and this is accomplished by means of inwardly and upwardly inclined folder bars 31 (Fig. 1). In the event that flaps 30 should be inclined toward one another instead of away from one another as the case enters the machine, a second pair of oppositely angled guides 32 is provided. Bars 31 and guides 32 are supported by the upper flap heaters. As the case enters the machine the operator holds down the inner case flaps by hand until the front edge of the rear inner flap passes beneath the central inner flap holding rail 33 which extends longitudinally of the machine from the front end to

a point just in front of the sealing pressure section D.

At position H (Fig. 1) the flap inner surfaces are in contact with the heating surfaces of the four flap heaters (preferably electric) of heating section A, two provided at the top and two at the bottom, one heater for each flap.

After the case has remained at position H, that is with the flaps within the heaters of heating section A, for a period of about six seconds the operator pushes another filled case into the entrance of slideway 1, and this succeeding case closes starting switch 26 a second time and conveyer chains 3 again move to advance the first case from position H through the adhesive applying mechanism B and flap closing section C to position S shown by dot and dash lines in Fig. 1, where the case is within the sealing pressure mechanism D.

The adhesive applying mechanism includes four similar units, one for each flap, and a detailed description of only one will be given. Each of the adhesive applying devices has an elongated stationary vertical casing 49 which is bracket mounted at its upper end.

Casing 49 has a vertical bore within which a tubular valve member 50 is fitted. On the side of casing 49 towards flap 30 the casing is provided with a narrow vertical slot (not shown) and valve member 50 also has a similar vertical slot. When valve member 50 is turned to bring these two slots into registry with one another, adhesive is allowed to flow outward onto the surface of flap, the flap being held in contact with the slotted mouth of casing 49 by means of a yieldably mounted pressure roller 53.

It is necessary to turn valve member 50 through only a small angle in order to cut off the flow of the adhesive. The supply of adhesive is admitted to the interior of tubular valve member 50 through a cored passageway in casing 49 and an opening in the side of valve member 50. The adhesive is led through suitable piping to the four applicators. This piping is indicated by numeral 56 and leads from an upper adhesive reservoir 57 to the adhesive applicators for the upper flaps. A second adhesive reservoir 58 is connected through similar piping 59 to the two lower adhesive applicators.

Reservoir 57 is mounted on the left-hand horizontal upper side frame member 60 of the machine and hence is raised or lowered with this frame member as the upper frame is adjusted for the purpose of adapting the apparatus for cases of different height. For this purpose the two side frame members 60 are secured to the upright posts 11 by means of bolts 61 which cooperate with vertical slot 62 in the posts. Consequently, considerable range of vertical adjustment is provided.

The lower adhesive reservoir 58 is mounted on the left-hand lower fixed side frame member 63 (Fig. 2). It is necessary to carry piping 59 from this reservoir downward to a point below the lower flap heaters in order to clear the downwardly extended flaps as they leave the heaters and pass into engagement with the adhesive applicators. The yieldable rollers 53 are of the same height as the adhesive applicators 49 and are each pivotally mounted on a forked lever 64 (Fig. 1) which is pivoted at 65 on a bracket 66 mounted on a part of one of the flap heaters. Rollers 53 are urged towards the applicator casings 49 by tension springs 53a.

Each of the tubular valves 50 of the four ad-

hesive applicers is provided with an actuating lever 67 to turn the valve to control the flow of adhesive. The mechanism for simultaneously actuating these four valves 50 so as to properly control the application of adhesive to the flaps is illustrated more particularly in Figs. 1, 2, and 3. Actuating lever 67 for the two lower valves 50 is connected by links 68 pivoted at their outer ends to operating arms 69 which are pinned to an operating cross-shaft 70 pivoted for rocking movement 10 in the lower side frame members 63. Similarly the two upper valve members 50 are connected to an upper operating cross-shaft 71, the linkage being identical and illustrated in Fig. 3 without the application of reference numeral thereto. The two operating shafts 70 and 71 are interconnected for simultaneous rocking movement by means of a link 72 which is pivoted to two equal length arms 73, one pinned to each of the respective shafts 70 and 71.

Rock shafts 70 and 71 are actuated by means of a cam device 74 mounted on a cam shaft 75 in a manner to be described. A roller 76 engages the face of cam member 74 and is carried by a lever 77 pivoted at its lower end to the frame of the machine and at its upper end by a link 78 which transfers the movement of the lever to an arm 79 pinned to lower rock shaft 70. Roller 76 is held against cam device 74 by two tension springs 70a shown in Fig. 1. Cam shaft 75 is chain connected to shaft 15 by means of a sprocket chain 80 passing over suitable sprockets on the respective shafts.

Cam device 74 is arranged to effect the opening of the valves 50 of the glue applicers in timed relation to the arrival of the forward ends of the case flaps between the housings 49 of the glue applicers and the pressure rollers 53. It also cuts off the glue at the centers of the flaps, skipping a short space where the outer flaps contact the edges of the inner flaps when closed, and then re-opens the applicer valves, finally closing them as the rear edges of the flaps leave the adhesive applicers.

The instant of opening and finally closing the valves varies with the length of the case and so also does the skipping point. In order that such adjustments may be made, cam device 74 includes four flat plates mounted in contact with another (Fig. 2). The innermost plate is keyed to cam-shaft 75 and the other three plates are loose on the shaft and angularly adjustable in position by means of a pair of bolts 81 which are received in arcuate slots in the three cam plates and are threaded into the fourth plate. The cam formations on the three cam plates are shown in side view in Fig. 1, the short lobe 82 constituting the skip-opening-and-closing cam.

As the cycle of the machine continues and the rear ends of the flaps of the case, passing from the heating section A to sealing pressure section D, emerge from the glue applicers 49, their forward edges engage two pairs of stationary warped surface flap folding or closing members 89 (Figs. 1, 2, and 3). Upper closing members 89 turn the two outer flaps from the vertical position in which they left the glue applicers toward one another and fold them into horizontal position bringing their inner heated surfaces, to which the adhesive has been applied, into contact with the surfaces of the inner flaps which are held in closed horizontal position against the contents of the case by rail 33. Similarly the lower flap folders 90 fold the bottom outer flaps into an engagement with the bottom inner flaps, the

pointed end portion 5 of supporting table 4 allowing this movement.

In the continued advance of the case it arrives at position S on belt 6 which supports the case at the sealing pressure section D. At this point the flight-bar 9 at the rear of the case engages the operating lever of a normally closed stopping switch 91 (Fig. 1) and opens the same thereby stopping motor 21 which operates the conveyer.

The opening of stopping switch 91 also causes the operation of the sealing pressure mechanism at station D and immediately places the flaps of the case under sealing pressure. This apparatus at station D comprises a rectangular pressure plate 92 of a size to accommodate the largest shipping case which the apparatus is adapted to handle. Presser plate 92 is suspended from the lower ends of four rods 93 which are vertically slidable in apertures in a supporting structure 94 mounted on the two upper side frame members 60. Rods 93 have collars 95 fixed to them to limit the upward movement of presser plate 92, and coil springs 96, which surround the upper portions of each of rods 93, rest upon the upper surface of supporting structure 94 and engage collars 97 fixed at the upper ends of rods 93. Springs 96 normally hold rods 93 and presser plate 92 in their uppermost positions as determined by the contact of collars 95 with the lower surface of structure 94.

Presser plate 92 is forced downwardly by means of an air cylinder 98 having a vertically reciprocating piston 99 therein which operates presser plate 92 through a piston rod 100. Air is supplied to cylinder 98 from a supply line 101 through a control valve 102 and an interconnecting pipe 103, valve 102 being electromagnetically operated by means of a solenoid 104. When solenoid 104 is energized, air control valve 102 is actuated to cut off air cylinder 98 from air pressure supply pipe 101 and to open the interior of the cylinder above the piston to atmosphere through exhaust connection 105. When the solenoid is de-energized the reverse operation takes place and the air pressure is connected to cylinder 98 and forces piston 99 and presser plate 92 downwardly compressing springs 96 and applying the desired sealing pressure to the shipping case at position S.

In Figs. 4-7 inclusive a modified form of glue applicer is illustrated. In this modification, the adhesive, instead of being extruded or ejected under pressure under the control of a valve mechanism, is applied by means of an adhesive-carrying roll which is rotated at the same surface speed as the linear speed of the flap, and with which the flap is brought into contact. The adhesive applying roll is coated with a film of adhesive of the desired thickness and such film is taken up by the surface of the flap. In the present machine the flaps are opened to the 90° position in respect to the surface of the case. This requires that the glue rollers rotate on vertical axes and consequently something of a problem is presented in maintaining the glue applying roll coated with a film of the desired uniform thickness. Also, because of the fact that the glue applying mechanism must be disposed between the two pairs of vertically positioned flaps, the minimum width of case which can be accommodated in the machine is determined by the thickness of the glue applying device. In other words, the minimum width of the case is about twice the thickness of the glue applying mechanism and one of the prob-

lems is to provide this mechanism with the necessary adhesive reservoir, applying roll and roll coating mechanism, and still permit the carton closing and sealing machine to operate on shipping cases of comparatively small width, for instance in the neighborhood of eight inches.

Referring now to Figs. 5 and 6 the modified form of glue applying mechanism comprises a vertical housing 133, conveniently made in the form of a casting, and in which are contained an adhesive reservoir 134, a vertical adhesive applying roll 135 and a shallow sump 136 for collecting surplus adhesive from roll 135. For convenience housing 133 is made with a removable bottom 133a held in place by screws as indicated in Fig. 7.

Glue roll 135 is keyed to an operating shaft 137 which projects from the top of housing 133 and on the upper end of which a driving sprocket 138 is fixed. Shaft 137 is rotated continuously during the operating cycle of the machine, that is, while a case is passing from position H to position S. For this purpose sprocket 138 may be connected by means of a chain 139 to any convenient rotating shaft of the machine.

At its lower end, shaft 137 is reduced in diameter and is supported in a stationary sleeve-like bearing 140 which projects upwardly from bottom member 133a. Turning on the outer surface of bearing projection 140 there is a gear 141 whose teeth mesh with the teeth of a second gear 142 forming a gear pump for supplying adhesive under pressure for application to the surface of roll 135. Pump gears 141, 142 rotate in recesses cored in bottom member 133a. Since it is necessary to operate the pump gears at a higher rotating speed than that of shaft 137, the pump gears are driven by a second vertical shaft 143 whose lower end is connected to drive gear 142 and whose upper end has secured to it a pinion 144 which meshes with a gear 145 keyed to shaft 137.

Gear pump 141, 142 discharges adhesive into the lower end of a vertical passageway 146 which may be recognized in Fig. 5 by its nearly semi-circular cross-section. The pressure supplied by the pump is sufficient to cause the adhesive to rise to the top of this passage. From this passage the adhesive is distributed into a narrow or thin substantially semi-cylindrical space 147 which extends from the bottom to the top of casing 133 adjacent glue roll 135 so that the surface of the adhesive applying roll 135 as it rotates is brought in contact with the adhesive under pressure in this shell-like semi-cylindrical space 147.

Roll 135 rotates in the counter-clockwise direction as shown in Fig. 5, as shown by the arrow, and the adhesive carried forward by the surface of the roll is reduced to a thin film of the desired thickness by means of a substantially square metal scraper 148, one corner of which is placed close to but out of contact with the surface of roll 135. Scraper 148 is mounted on a pivot shaft 149 which is disposed in a recess in casing 133 parallel with shaft 143. At the upper end an adjusting handle 150 is keyed to shaft 149 and the whole structure may be locked in the position to which it is adjusted by means of a screw 151 passing through an arcuate slot 152 in a part of handle 150 and threaded into casing 133.

In order to prevent adhesive from escaping freely from the upper end of the shell-like semi-cylindrical space 147 a doctor roll 153 is pro-

vided which is preferably a hardened roll made for example of stainless steel and the surface of which rotates close to but slightly spaced from the surface of glue applying roll 135 so as not to wear the surface of this roll since it is preferably made of softer material, such for example as bronze.

The doctor roll 153 is driven in the same direction of rotation as shaft 137 by means of a short sprocket chain 154 which connects two sprockets, one keyed to the upper end of shaft 137 and the other fixed on the upper end of a shaft 155 on which doctor roll 153 is mounted. The contiguous surfaces of rolls 135 and 153 consequently move in opposite directions. A negligible amount of adhesive continuously escapes between these surfaces and is collected in sump 136.

A shell-like semi-cylindrical space 156 extends around the rear surface of doctor roll 153 and is in communication with the similar space 147 previously described. Space 156 consequently is always filled with adhesive. This space is completely closed, however, by means of an adjustable scraping blade 157 the edge of which is adjusted into contact with hardened roll 153 and held in position by means of clamping screws 158.

The glue roll 135 and gear pump 141, 142 operate a large part of the time with no flap in contact with the glue roll. During this time the film of adhesive which is carried forward by roll 135 past scraper 148, collects in sump 136 together with the adhesive which flows out between doctor roll 153 and roll 135. This adhesive is continuously pumped into the vertically disposed passage 146 by the gear pump, a passage being cored from sump 136 in the bottom member 133a of the casting. This passage is indicated by numeral 159 (Fig. 7) and delivers the adhesive to the teeth of gear 141 by which it is carried around to passage 146. It will be understood that gear 142 receives adhesive from the bottom of reservoir 134. The vertically disposed passage 146 is provided at its upper end with an overflow outlet 160 through which adhesive can be returned to reservoir 134. Sump 136 is provided with a screen 161 which removes particles of lint or other foreign matter which are apt to be carried by the surfaces of flaps and deposited on glue roll 135.

It will be understood that one of the adhesive applying devices above described may be mounted on the carton closing and sealing apparatus in place of each of the valve type adhesive applicators 49, in which event there will be four roll type adhesive applicators, two above and two below the case slideway 1. In Fig. 4 one such adhesive applicator is shown as operating upon a top flap 30 and a second upon a bottom flap 28. Outer flap guide rolls 162 are mounted on stationary supporting brackets 163 to support the outsides of the flaps and hold the flaps against the glue rolls. The only difference between these upper and lower adhesive applicators is that shafts 137 and 143 are extended through the bottom of the casing 133m of the lower device instead of through the top. Consequently the operating sprockets and gears are located at the bottom instead of the top.

This being the only difference, the remainder of the description will be confined to an upper glue applicator. The casing 133 of the device is pivotally mounted on a vertical stationary rod 164 which may be secured to a bracket similar to bracket 46 (Fig. 2). Rod 164 is received in aligned apertures in two spaced lugs 165 which project from the rear of casing 133, and a collar

166 is adjustably fixed on rod 164 beneath one of these lugs thereby pivotally supporting casing 133 on the rod.

If it is desired to apply adhesive throughout the length of the case flaps pivotal support of the glue applying device is unnecessary and the front end of casing 133 may be fixed in any suitable manner to the frame of the closing and sealing machine. If, however, it is desired to omit the adhesive from the center of the flap, that is, to "skip-glue" the flaps, casing 133 is swung about pivot shaft 164 to move glue roller 135 out of contact with the case for a short interval while the center of the flap is passing the roll. This may be accomplished by means of the cam device 74 and the system of links and rock-shafts previously described for operating the valves 50. With this modified form of glue applier, however, cam device 74 is re-assembled with only the cam plate which has the single cam lobe 82, as this single short cam will effect the momentary removal of glue roll 135 from the center of the flap.

With the closing and sealing apparatus assembled with the vertical-roll type glue applying devices of Figs. 4-7 in place of the glue appliers 49, rods 68m are substituted in place of links 68 which actuate the four valve members 50, the new rods being similar to the old but of different length. Each of rods 68m is connected to swing one of the adhesive device casings 133 on its supporting pivot shaft 164 by mechanism such for example as is shown in Fig. 5. The end of rod 68m is pivoted to one arm of a bell-crank lever 167 which is pivoted at 168 to a bracket 169 supported in any convenient manner on the frame of the machine. The other arm of lever 167 is pivoted at 170 to a short link 171, the opposite end of which is pivoted at 172 to the outer end (upper end in Fig. 6) of casing 133. This linkage mechanism is therefore above the tops of the extended upper flaps and below the bottoms of the extended lower flaps.

In the improved case closing and sealing apparatus the case flaps are unfolded only 90° to vertical position instead of being rotated through an angle of 180° and extended horizontally from the opposite sides of the case, as has heretofore been customary in commercial apparatus of this kind. The rotation of the flaps to vertical position only, permits the width of the apparatus to be considerably reduced. Moreover, the flap heaters are easily applied to the vertically extended flaps. In addition, the utilization of heaters for heating the flaps prior to the application of the adhesive so shortens the time of the setting of the adhesive as to make it possible to employ the reciprocating presser plate type of compression unit in which the cases are held in stationary position until the adhesive has set. This arrangement greatly reduces the overall length of the apparatus.

The embodiments of the present invention which have been illustrated as exemplifying the apparatus of the invention have been described in considerable detail, but it will be understood that numerous changes can be made in the arrangement and construction of the apparatus without departing from the spirit of the invention or from the scope thereof as defined in the appended claims.

We claim:

1. An adhesive applying device adapted to be disposed in the path of travel of a case flap to apply adhesive to a surface thereof comprising a casing containing an adhesive reservoir and a

5 sump, an adhesive applying roll mounted in said casing for rotation on a vertical axis and adapted to contact the case flap and to coat the same with adhesive, an adhesive circulating system within said casing including pump means for withdrawing adhesive from said reservoir and disposing it on the surface of said roll, an adjustable scraper cooperating with said roll to reduce said adhesive to a thin film and to control the thickness thereof, a doctor roll cooperating with said adhesive applying roll at an angular distance from said scraper to prevent the free flow of adhesive from said circulating system, said doctor roll being disposed with its surface contiguous but out of contact with that of said adhesive applying roll, means for driving said rolls so that said contiguous surfaces move in opposite directions thereby permitting only a negligible amount of adhesive to escape between them, said sump being disposed to collect such adhesive and adhesive from said adhesive applying roll, and pump means for withdrawing adhesive from said sump and returning it to said circulating system.

2. An adhesive applying device constructed and arranged to be disposed in the path of travel of a substantially vertical case flap to apply adhesive to a surface thereof comprising a casing containing an adhesive reservoir, an adhesive applying cylinder mounted in said casing for rotation on a substantially vertical axis and constructed and arranged to engage said flap to coat the same with adhesive, a doctor roll disposed at one side of said cylinder with its surface contiguous to but out of contact with that of said cylinder, means for driving said cylinder and said roll so that said contiguous surfaces move in opposite directions thereby permitting only a negligible amount of adhesive to escape between them, a sump to collect such adhesive, an adhesive receiving chamber formed in said casing on the opposite side of said cylinder and roll from the case flap, a scraper coating with said doctor roll to prevent escape of adhesive from said chamber, an adjustable scraper cooperating with said cylinder to reduce the adhesive received on said cylinder from said chamber to a thin film and to control the thickness thereof for application to the flap, an overflow passage into said reservoir at the top of said recess, and pump means for withdrawing adhesive from said reservoir and from said sump and supplying it to said recess thereby continuously recirculating the adhesive.

3. In a machine of the class described, means for conveying a succession of cases along a horizontal path of travel with the outer or side flaps thereof extending vertically from the cases, and adhesive applying means disposed in stationary position between the paths of said vertical flaps for applying adhesive to the inner vertical surfaces of the flaps of said successive cases.

4. In a machine of the class described, means for conveying a case along a path of travel with the outer or side flaps thereof extending substantially vertically from the case, and adhesive applying means for applying adhesive to the inner substantially vertical surfaces of said flaps comprising a substantially vertical rotating cylinder engaging each of said flaps, a casing for each of said cylinders disposed between said substantially vertical flaps, said casing also containing an adhesive reservoir and a sump, an adhesive circulating system within said casing including pump means for withdrawing adhesive from said reservoir and disposing it on the surface

of said cylinder, an adjustable scraper cooperating with said cylinder to reduce said adhesive to a thin film and to control the thickness thereof, said sump being disposed to collect said adhesive from said cylinder, said pump means also withdrawing adhesive from said sump and returning it to said circulating system.

5. In a machine in the class described, means for conveying a case along a path of travel with the outer or side flaps thereof extending substantially vertically from the case, and adhesive applying means for applying adhesive to the inner substantially vertical surfaces of said flaps comprising a substantially vertical rotating cylinder engaging each of said flaps, a casing for each of said cylinders disposed between said substantially vertical flaps, said casing also containing an adhesive reservoir disposed in upstanding position alongside of said cylinder, and a shallow sump, an adhesive circulating system within said casing including pump means for withdrawing adhesive from said reservoir and disposing it on the surface of said cylinder, an adjustable scraper cooperating with said cylinder to reduce said adhesive to a thin film and to control the thickness thereof, said shallow sump being disposed at the bottom of said casing to collect adhesive from said cylinder, said pump means being disposed between said shallow sump and the bottom of said upstanding reservoir, and an inlet passage to said pump from said sump as well as from said reservoir.

6. In a machine of the class described, means for conveying a succession of cases along a horizontal path of travel with the outer or side flaps

thereof extending vertically from the cases, and a plurality of adhesive applying means disposed in stationary positions between the paths of said vertical flaps for applying adhesive to the inner surfaces of the flaps of said successive cases, each of said adhesive applying means comprising a casing having an adhesive reservoir, an adhesive applying roll mounted in said casing for rotation on a vertical axis, an adhesive circulating system within said casing including pump means for withdrawing adhesive from said reservoir and disposing it on the surface of said roll, means for allowing the surplus to return to the reservoir, and an adjustable scraper cooperating with said roll to reduce said adhesive to a thin film and to control the thickness thereof, said casing not being substantially wider in a direction normal to the paths of the vertical flaps than said roll, and the reservoir being disposed in upright position substantially parallel therewith and with the paths of the vertical flaps.
